UNITED STATES PATENT OFFICE.

ANTON J. HAUG AND RICHARD J. HAUG, OF NASHUA, NEW HAMPSHIRE, SAID RICHARD J. HAUG ASSIGNOR TO SAID ANTON J. HAUG.

PROCESS AND MACHINE FOR THICKENING PULP.

Application filed October 4, 1927. Serial No. 223,897.

This invention relates particularly to processes of and machines for performing the various screening or straining operations to which paper pulp is subjected in the course of preparing it for the paper making operation. The invention will be herein disclosed as embodied in a pulp thickening machine, although it is contemplated that some features of the invention may be applied to other uses, and the term "pulp" is therefore used in a generic sense to include other materials which the machine is adapted to handle.

Pulp thickeners are used in the paper making industry to strain out surplus water in which the solid constituents of the pulp are suspended and thus to concentrate the pulp more or less. The present invention aims to devise a machine which will perform this operation rapidly and efficiently, will have a large capacity in proportion to its size, and will be economical to manufacture. An especially important feature of the invention resides in the construction of the straining drum. The invention also aims to improve the means for removing the thickened pulp from the straining surface with a view to effecting such removal continuously, providing for the proper control of the thickness of the layer of pulp on the straining surface, and avoiding any possibility of injury to said surface.

The nature of the invention will be readily understood from the following description when read in connection with the accompanying drawings, and the novel features will be particularly pointed out in the appended claims.

In the drawings,

Figure 1 is a view, partly in side elevation and partly in longitudinal vertical cross-section, showing a pulp thickening machine constructed in accordance with this invention;

Fig. 2 is a plan view, partly in cross section, of the machine shown in Fig. 1 but showing it equipped with a mechanism for reciprocating the spray pipe;

Fig. 3 is a vertical, transverse, cross-sectional view substantially on the line 3-3, Fig. 2;

Fig. 4 is a perspective view of the gate at the discharge end of the intake spout and the adjusting mechanism therefore;

Fig. 5 is a perspective view showing certain details of construction of the straining drum;

Fig. 6 is a longitudinal, cross-sectional

view through one side of the drum shown in Fig. 5; and

Figs. 7 and 8 are cross-sectional views showing details of the construction of the drum.

Referring first to Figs. 1, 2 and 3, the machine there shown comprises a rotary straining drum, indicated in general at 2, this drum being mounted on one end of a horizontal shaft 3 which is supported in bearings 4-4 mounted on a base 5. The shaft 3 is provided with a pulley 6 by means of which the machine may be belted to any convenient source of power. A casing encloses the drum 2 and comprises end pieces 7 and 8, respectively, both mounted on the base 5, and a circumferential section 10 which may be removed to permit access to the drum 2. Preferably the two end pieces 7 and 8 are divided horizontally for convenience in manufacture and assembling.

It will be seen from an inspection of Fig. 1 that the drum comprises a disk-like head 12 which is provided with a hub to receive the shaft and that it also includes a ring 13 at the opposite end of the drum, this ring being of channel shape in cross-section to receive a flange 14 on the casing member 8. The ring 13 and head 12 are rigidly connected together by parts which will be described later in detail, and the straining surface 15 is located between the ring and head. This straining surface or sieve is of circular form in cross-section and it may be either tapered or cylindrical, but preferably is slightly tapered, as clearly shown in Fig. 1, the larger end of the drum being closed by the head 12, and the smaller end being open.

The pulp to be thickened usually is very dilute, containing only a small percentage of fibre or other solid matter, and this pulp is conducted into the drum through an inlet spout 16 which is supported in the end piece 8 of the casing. The spout is curved as clearly shown in Figs. 1, 2 and 3, and is provided with a substantially horizontal discharge outlet at its lower end. The stock to be thickened may flow into the intake spout from a head box or any other suitable arrangement, but usually runs in at a relatively low velocity.

In order to control the delivery of this stock or pulp to the straining surface, a gate 17 is mounted in the discharge end of the spout 16, and provision is made for adjust-

ing the gate to control the width of the aperture through which the pulp is discharged. Preferably this gate is in the form of a half cylinder, as shown in the drawings, and is secured to a horizontal shaft 18 which is supported in two bearings 20-20 at the opposite ends of the discharge opening of the spout. This shaft also projects through the end piece 8 of the casing, as best shown in Fig. 4. Secured to the outer end of this shaft is a sector 21 having a slot 22 therethrough to receive a bolt 23 which is threaded into the casing member 8. This construction permits the adjustment of the gate 17 from a point outside the casing and while the machine is in operation, the bolt 23 serving to hold the gate in its adjusted position.

Preferably the discharge end of the inlet spout is curved in the direction of revolution 20 of the drum, as shown in Fig. 3, and the gate 17 should be so adjusted that when the machine is in operation a layer of pulp of suitable thickness flows continuously on to the straining surface 15 in the direction of revolution of said drum. The drum should be revolved at such a speed as to create a very substantial centrifugal force which throws the water in the pulp forcibly through the straining surface and into the casing where 30 it drains out almost immediately through an outlet spout 24, Fig. 3, no part of the straining surface preferably being submerged in water at any time. The solid constituents of the pulp collect in a thickened mass on the inner side of the straining surface. Preferably 35 this surface or strainer 15 consists of wire fabric, and in order to avoid any possibility of injury to it, a novel arrangement has been provided for moving the thickened pulp 40 across the surface of the strainer and ejecting it from the drum.

As shown, this apparatus includes a spray pipe 25 supported in the casing member 8 and extending into the drum closely adjacent 45 to the lower side thereof. This pipe is designed to be connected with a supply of water or other fluid under pressure through a valve 26, Fig. 1, and it is provided inside the drum with a series of outlet apertures arranged to 50 direct jets of water against the thickened pulp, these jets being so inclined that they act on the pulp to force it across the straining surface of the drum toward the smaller or outlet end thereof. The velocity of the 55 water or other fluid in the jets which perform this ejecting operation can be controlled by adjusting the valve 26. This arrangement thus effectually discharges the pulp from the drum while avoiding the use of mechanical 60 scrapers which might injure the wire fabric.

The spraying mechanism just described moves the thickened pulp into the range of operation of a scraper 27; Figs. 1, 2 and 3, which is secured to the casing member 8 and 65 is provided with an inclined edge spaced

slightly from the inner surfaces of the ring 13, previously referred to, and another ring 28 which lies between the ring 13 and the screen 15. The rotary motion of the drum carries the thickened pulp against this scraper which lifts it and diverts it outwardly toward the discharge chute 30, Fig. 1. Some of this pulp will be thrown outwardly into the chamber 31, Fig. 1, which is formed in the outer part of the casing 8, and this pulp will be removed and discharged by one or more scrapers 32 which are secured to ring 13.

As above stated, a tapered construction of strainer drum is preferred, one reason being that this shape avoids the tendency of the stock to move toward the discharge end of the drum before it has come sufficiently under the control of centrifugal force. It thus permits a more accurate control of the discharging movement of the thickened pulp.

In some cases it may be desirable to traverse or reciprocate the spray pipe 25 longitudinally thereof, and this operation may conveniently be performed by a mechanism such as that shown in Fig. 2. In this arrangement the spray pipe 25 is mounted in a guide 33 so that it can move longitudinally, and a lever 34 is connected to the spray pipe, this lever being operated by a link 35 which is pivoted to another lever 36 having a slot 37 in one end thereof. An eccentric pin 38 works in this slot and is mounted in a spiral gear 40 which is arranged to be rotated slowly by a worm wheel 41, this worm wheel being secured fast on the shaft 3.

For an understanding of the details of construction of the strainer drum, reference should be made more particularly to Figs. 1, and 5 to 8, inclusive. It will be observed that the wire fabric 15 which forms the strainer element is supported at the inner edges of clamping rings 42-42, arranged in pairs. Each pair of these rings is circumferentially grooved near its inner margin, as best shown in Fig. 7, to receive the fabric and a rod or 110 wire 43 which is located in the groove between cooperating rings. This rod assists in clamping the wire fabric securely between the rings and in stretching the fabric as the rings are drawn together by bolts 44. This construction also secures the wire fabric 15 firmly to the clamping rings.

In order to hold these rings in proper relationship to each other, and also for the purpose of adjusting them to stretch the wire, 120 they are mounted on a series of threaded rods 45. These rods are threaded into the drum head 12 and are rotatably mounted in the ring 13. Adjusting nuts 46 are mounted on on each rod immediately beside each of the 125 rings, and by properly manipulating these nuts in a manner which will be obvious from an inspection of Figs. 5 and 6, the rings 42 can be moved axially of the drum to stretch the wire fabric in an axial direction. The 130

necessary slip between the right-hand ring 42', Fig. 6, and the channel shaped ring 13 is provided by the short tubular extension 28 of the ring 42'. The right-hand pair of clamping rings 42-42' is drawn toward the channel ring 13 by a series of bolts, one of which is shown at 47 in Figs. 5 and 8.

The wire fabric 15 may consist of a wide web, the width being disposed axially of the drum, and the ends may be brought together and secured in grooves formed in abutting faces of the split ends of the rings, as shown in Figs. 3 and 5, a rod or wire 48 being used in the grooves to assist in clamping the wire in place, just as the rod 43 cooperates with the rings 42. The split sections of the rings are drawn together by bolts 50, Fig. 5, to clamp them on the rod and on the fabric. Preferably, also, the ends of the rings are bevelled, as shown at 51; Fig. 5, and the bevelled ends of adjacent rings overlap each other to hold them in contact while permitting the axial adjustment of adjacent pairs of rings relatively to each other, as above described.

In order to support the wire fabric 15 against the forces set up by centrifugal inertia, the clamping rings 42 are provided with flanges 52-52' which bear against the outer surface of the fabric, the fingers of adjacent rings where they project toward each other being staggered, as clearly shown in the drawings, so that relatively short sections only of the fabric are left unsupported.

It will now be appreciated that the invention provides a drum construction in which the difficulties of handling a wire fabric have been successfully overcome, the drum having a smooth inner surface, which is very desirable, and also having provision for stretching the fabric tightly. At the same time the expense of manufacturing the drum is within reasonable limits. By adjusting the valve 26 or regulating in any other way the pressure of the water or other fluid used to effect the movement of the thickened pulp across the straining surface, the rate of such movement can be controlled and the thickness of the layer of thickened pulp maintained on the inner surface of the strainer can be governed.

The invention thus provides a pulp thickening machine of unique organization, which can be manufactured economically, is efficient, and has a very high capacity in proportion to its size. While a preferred embodiment of the invention has been above described, it will be understood that the invention may be embodied in other forms without departing from the spirit or scope thereof. Also, that the method devised by this invention may be practiced with the aid of a great variety of forms of apparatus.

Having thus described our invention, what we desire to claim as new is:

1. In a machine of the character described,

the combination of a straining surface, means for delivering pulp in suitable relationship thereto to cause liquid constituents of the pulp to pass through said surface and solid constituents to accumulate thereon, and means for directing fluid under pressure against such accumulation to move it across said surface.

2. In a machine of the character described, the combination of a tapered rotary strainer drum of approximately circular cross-section mounted to revolve about an approximately horizontal axis, means for delivering pulp to the interior of said drum whereby liquid constituents of the pulp will pass through the straining surface and solid constituents will accumulate upon said surface, and means for acting on said solid constituents to move them across the drum toward one end thereof.

3. In a machine of the character described, the combination of a tapered rotary straining drum of approximately circular cross-section mounted to revolve about an approximately horizontal axis, means for delivering pulp to the interior of said drum whereby liquid constituents of the pulp will pass through the straining surface and solid constituents will accumulate upon said surface, and means for acting on said solid constituents to move them across the drum toward the smaller end thereof.

4. In a pulp thickening machine, the combination of a rotary straining drum, means for delivering pulp to the interior of said drum whereby a part of the liquid therein will pass through the straining surface and the thickened pulp will accumulate on the said surface, and means for directing one or more jets of fluid under pressure against said thickened pulp to move it across said straining surface.

5. In a pulp thickening machine, the combination of a rotary straining drum, means for delivering pulp to the interior of said drum whereby a part of the liquid therein will pass through the straining surface and the thickened pulp will accumulate on said surface, a scraper for ejecting the thickened pulp from said drum, and means for directing one or more jets of fluid under pressure against said pulp to transfer it across said surface into the range of operation of said scraper.

6. In a pulp thickening machine, the combination of a rotary straining drum, means for delivering pulp to the interior of said drum whereby a part of the liquid therein will pass through the straining surface and the thickened pulp will accumulate on said surface, means for directing one or more jets of fluid under pressure against said thickened pulp to move it across said surface, and means for regulating the rate of advance of said thickened pulp across said surface.

7. In a pulp thickening machine, the com-

- bination of a rotary straining drum, means for delivering pulp to the interior of said drum whereby a part of the liquid therein will pass through the straining surface and the 5 thickened pulp will accumulate on said surface, means for directing a jet of fluid under pressure against said thickened pulp to move it across the straining surface, and means for traversing said jet.
- 10 8. In a pulp thickening machine, the combination of a rotary straining drum, means for delivering pulp to the interior of said drum whereby a part of the liquid therein will pass through the straining surface and 15 the thickened pulp will accumulate on said surface, and a spray pipe projecting into said drum and having outlet apertures arranged to direct jets of water against said thickened pulp at inclinations serving to move said 20 pulp across the straining surface toward one end of said drum.
9. In a pulp thickening machine, the combination of a rotary straining drum, an inlet 25 spout for delivering pulp to the interior of said drum, and means located substantially at the discharge end of said spout for regulating the delivery of pulp to said drum.
10. In a pulp thickening machine, the combination of a rotary straining drum, an inlet 30 spout for delivering pulp to the interior of said drum, and a gate located substantially at the discharge end of said spout and adjustable to vary the size of the discharge aperture of said spout.
- 35 11. In a pulp thickening machine, the combination of a straining drum of approximately circular cross-section, means supporting said drum for rapid rotation about a substantially horizontal axis, an inlet spout for 40 delivering pulp to the interior of said drum whereby thickened pulp will accumulate on the straining surface of the drum, a pivoted gate located substantially at the discharge end of said spout and adjustable to vary the 45 size of the discharge aperture of said spout, and means whereby said gate may be adjusted while the machine is in operation.
12. In a pulp thickening machine, the combination of a straining drum of approximately 50 circular cross-section, means supporting said drum for rapid rotation about a substantially horizontal axis, a casing in which said drum is mounted, an inlet spout leading into said drum for conducting pulp into the 55 interior of the drum, a spray pipe projecting into said drum and having outlet apertures therein for directing jets of water against the thickened pulp on the inner surface of the drum to force it toward one end of the drum, 60 and a scraper cooperating with said drum at the discharge end thereof to eject the thickened pulp from the drum.
13. In a pulp thickening machine, the combination of a straining drum of approximately 65 circular cross-section, means supporting said drum for rapid rotation about a substantially horizontal axis, said drum being tapered and having a smooth interior surface, an inlet spout leading into one end of said drum for delivering pulp to the inner surface 70 of the drum, and a spray pipe projecting into said drum and having outlet apertures arranged to direct jets of water against the thickened pulp on the straining surface of the drum to move said pulp across the said surface toward the smaller end of said drum.
14. A straining drum for pulp thickening machines and the like, comprising a porous fabric strainer, and supporting means for holding said strainer in an approximately 75 circular form with the inner surface thereof substantially smooth.
15. A straining drum for pulp thickening machines and the like, comprising a porous fabric forming the straining surface of the 80 drum, and supporting means for said fabric including members adjustable to stretch the fabric.
16. A straining drum for pulp thickening machines and the like, comprising a wire fabric 85 forming the straining surface of the drum, and supporting means for said fabric including members to which the fabric is attached, said members being adjustable to stretch the fabric axially of the drum.
17. A straining drum for pulp thickening machines and the like, comprising a wire fabric forming the straining surface of the drum, and supporting means for said fabric including members to which the fabric is attached, 90 said members being adjustable to stretch the fabric circumferentially.
18. A straining drum for pulp thickening machines and the like, comprising a wire fabric forming the straining surface of the drum, and supporting means for said fabric including members adjustable to stretch the fabric both circumferentially and axially.
19. A straining drum for pulp thickening machines and the like, comprising a wire fabric forming an approximately circular strainer, and supporting means for holding said fabric in its operative position including clamping rings grooved to receive said fabric, and means cooperating with said rings 110 to clamp them on the fabric.
20. A straining drum for pulp thickening machines and the like, comprising a wire fabric forming an approximately circular strainer, supporting means for holding said 115 fabric in its operative position including clamping rings grooved to receive the fabric, rods cooperating with the fabric to hold it in said grooves, and means cooperating with said rings to clamp them on the fabric and on 120 said rods.
21. A straining drum for pulp thickening machines and the like, comprising a wire fabric forming an approximately circular strainer, and supporting means for said strainer in- 125 130

- cluding a series of rings encircling said strainer and having fingers projecting therefrom and bearing against the outer surface of the strainer.
- 5 22. A straining drum for pulp thickening machines and the like, comprising a wire fabric forming an approximately circular strainer, supporting means for said fabric including a series of clamping rings arranged in 10 pairs and encircling the strainer, said rings clamping portions of the fabric between their inner margins, and means for supporting said rings for axial adjustment to tighten said fabric.
- 15 23. A straining drum for pulp thickening machines and the like, comprising a wire fabric forming an approximately circular strainer, supporting means for said fabric including a series of clamping rings arranged in 20 pairs and encircling the strainer, said rings clamping portions of the fabric between their inner margins, threaded rods extending through said rings, and nuts on said rods for adjusting said rings to tighten the fabric.
- 25 24. That improvement in processes of thickening pulp, which consists in straining surplus water out of the pulp, and utilizing the action of fluid against the thickened pulp to move it across the straining surface.
- 30 25. That improvement in processes of thickening pulp, which consists in collecting the thickened pulp on a straining surface, and moving said thickened pulp across said surface by a jet of fluid under pressure.
- 35 26. That improvement in processes of thickening pulp, which consists in straining surplus water out of the pulp, and directing a plurality of jets of fluid against the thickened pulp at inclinations serving to eject it from 40 said surface.
- 45 27. That improvement in processes of thickening pulp, which consists in straining surplus water out of the pulp, directing a jet of fluid under pressure against the thickened pulp at an inclination serving to move it
- across the straining surface, and moving said jet to effect a further movement of said pulp across said surface.
28. That improvement in processes of thickening pulp, which consists in producing 50 a thickening action centrifugally upon the inner surface of a strainer drum, and forcing the thickened pulp along the straining surface by means of fluid pressure directed against said pulp.
29. That improvement in processes of thickening pulp, which consists in flowing a stream of pulp continuously into a revolving straining drum, rotating said drum at a sufficient speed to create centrifugal force serving 60 to propel the surplus water in the pulp through the straining surface and thereby collect the thickened pulp on said surface, and moving the thickened stock across said surface by directing a jet of fluid under pressure 65 against the pulp.
30. That improvement in processes of thickening pulp, which consists in flowing a stream of pulp continuously into a revolving straining drum, rotating said drum at a sufficient speed to create centrifugal force serving 70 to propel the surplus water in the pulp through the straining surface and thereby collect the thickened pulp on the said surface, utilizing said motion to scrape the thick- 75 ened stock out of said drum, and directing jets of fluid under pressure against the thickened pulp on said surface to move the pulp into position for said scraping action.
31. A straining drum for pulp thickening 80 machines and the like, comprising a porous fabric strainer, and supporting means for holding said strainer in an approximately circular form with the inner surface thereof substantially smooth, said supporting means 85 including parts bearing on the outer surface of the strainer at closely spaced intervals and supporting it against outward distortion.
